US0D1070605S

(12) **United States Design Patent** (10) **Patent No.:** **US D1,070,605 S**
(45) **Date of Patent:** ** *Apr. 15, 2025

(54) **DISPENSER**

- (71) Applicant: **S. C. JOHNSON & SON, INC.**,
Racine, WI (US)
- (72) Inventor: **Brian T. Davis**, Burlington, WI (US)
- (73) Assignee: **S. C. JOHNSON & SON, INC.**,
Racine, WI (US)
- (*) Notice: This patent is subject to a terminal disclaimer.
- (**) Term: **15 Years**
- (21) Appl. No.: **29/906,758**
- (22) Filed: **Nov. 9, 2023**

Related U.S. Application Data

- (63) Continuation of application No. 29/817,997, filed on Dec. 6, 2021, now Pat. No. Des. 1,018,319, which is

(57) **CLAIM**

The ornamental design for a dispenser, as shown and described.

DESCRIPTION

FIG. 1 is an isometric view of the top, front, and right side of the dispenser embodying my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is an isometric view of the top, front, and right side of an alternate embodiment of my design for a dispenser;
FIG. 8 is a front elevational view thereof;
FIG. 9 is a rear elevational view thereof;
FIG. 10 is a left side elevational view thereof;
FIG. 11 is a right side elevational view thereof; and,
FIG. 12 is a top plan view thereof.

1 Claim, 10 Drawing Sheets

Related U.S. Application Data

a continuation of application No. 29/781,734, filed on Apr. 30, 2021, now Pat. No. Des. 940,563, which is a continuation of application No. 29/722,096, filed on Jan. 27, 2020, now Pat. No. Des. 920,802, which is a continuation-in-part of application No. 29/710,489, filed on Oct. 23, 2019, now Pat. No. Des. 920,804.
